United States Patent Office

Des. 193,235
Patented July 10, 1962

193,235

SUN SHIELD OR SIMILAR ARTICLE

Elizabeth A. McNew, 8425 Sepulveda, Sepulveda, Calif.

Filed Jan. 18, 1961, Ser. No. 63,601

Term of patent 14 years

(Cl. D88—3)

FIG. 1

FIG. 2

FIG. 3

FIG. 1 is a perspective view of a sun shield or similar article, showing my new design.

FIG. 2 is a top plan view.

FIG. 3 is a side elevational view.

The dominant features of the design reside in the portions shown in full lines.

I claim:

The ornamental design for a sun shield or similar article, substantially as shown and described.
